UNITED STATES PATENT OFFICE.

WILLIAM N. PARKES, OF BROOKLYN, NEW YORK

LOOPER MECHANISM FOR SEWING MACHINES.

No. 875,623.

Specification of Letters Patent.

Patented Dec. 31, 1907.

Application filed September 9, 1905. Serial No. 277,774.

To all whom it may concern.

Be it known that I, WILLIAM N. PARKES, a citizen of the United States, residing in Brooklyn, county of Kings, and State of New York, have invented a new and useful Improvement in Looper Mechanism for Sewing-Machines, of which the following is a description.

This invention has reference to lock stitch sewing machines, and it belongs to the looper or hook mechanisms of such machines.

On June 9, 1903, U. S. Patent No. 730,692 was issued to applicant, in which an improved form of looper mechanism is shown, described and claimed.

The main object of my present invention is to make further improvements in looper mechanisms along the same lines disclosed in the said patent.

These improvements consist mainly of constructing the hook and bobbin case shown in the said patent so there is a better bearing between the said elements, and to so locate said bearing, that the bobbin case is better balanced in the hook, to improve the bobbin case relative to the delivery of the thread from the same, and to make certain other improvements in connection with protecting the thread from the beak of the hook, and in connection with the delivery of the needle thread loop from hook.

Referring to the drawings: Figure 1 is a view showing only so much of an organized sewing machine as is deemed necessary to illustrate the application of this invention, the location of the parts thereof and their co-operation with the other elements of the machine, the view being partially an end elevation and partially a transverse section taken across the frame of the machine at the end of the head of the latter; Fig. 2 shows in vertical section the several parts of the looper, thread case and bobbin, the parts being dismembered and shown in assembling position; Fig. 3 is a perspective view corresponding to the sectional view of Fig. 2; Fig. 4 is an elevation of the hook side of the looper, a portion being broken away so as to show the needle thread loop as it is about to be drawn from the looper through the space between the bearings of the parts; Fig. 5 is a view similar to Fig. 4, but showing a different position of the looper relatively to the thread case and the loop of needle thread about to escape from the looper through the space between the bearing of the parts, and Fig. 6

is a bottom plan view of the outer and inner hooks and co-acting parts.

In the drawings, *a* represents the frame of the machine, *b* the bearings and frame of the head, *c* the needle bar carrying the needle *d* and reciprocating in bearings of the needle gate or swinging frame *e*, the lower bearing of which is journaled at *f* about the presser bar *g*, carrying the foot *h*, co-operating with the feed dog *i* of an approved feed mechanism.

The numeral 1 indicates a large driving gear carried by the lower shaft (not shown) of the machine, said gear meshing with a pinion 2 carried by the shaft 3, journaled vertically in the frame of the machine in any approved manner, the said gear and pinion having a ratio of two-to-one so as to impart two rotations of the looper to one reciprocation of the needle and said pinion 2 being secured in place by means of screws 4 passing through the circular head 5 of the shaft 3, and tapped into said pinion. The head 5 is provided with the flange 6 upon which rests the main wall or body 7 of the looper, screws 8 passing through said wall 7 into the flange 9 of the head 5. The looper is provided with the depending wall or flange 10, having at its top the seat or ledge 11 and inner vertical wall 12 extending from said ledge. Between the body 7 and the depending wall 10 is a channel 13, substantially concentric with the axis of the looper, in which channel operates the auxiliary hook 14, carried by the plate 15, secured by means of screws 16 to the bottom 17 of the thread or bobbin case, the latter, in this instance, being provided with the tubular spindle 18, for supporting the bobbin 19. The thread case is provided with the circumferential flange 20, extending about almost its entire circumference, which flange is located at the top of the case, there being but a small space 21 omitted for the purpose of thread clearance. The thread case is also provided with the finger 22, which co-operates with a stationary part of the throat or cloth plate of the machine for preventing circular movement of the said case during the operation of the looper, as is usual. The looper is provided with the loop-taking hook 23, formed by cutting away a portion of the body 7, as at 24, and by forming an inclined slot or throat 25 for the reception of the needle loop. The end of the beak of the hook is located in a plane substantially parallel with the ledge 11 of the hook. The bobbin case is provided with a thread leading slot 26 that

terminates in a thread delivery opening 27. A thread guiding bar is connected to the case as shown in Fig. 5, this guiding bar serves to keep the bobbin thread from lopping down 5 and being caught by the point of the beak of the hook. This guide or guard 28 might be constructed so as to form a tension on the thread, but in the present form of construction the thread passes freely between the 10 guard 28 and the bobbin case. The bobbin is placed in the bobbin case, so that as the thread unwinds, the bobbin turns in an opposite direction to that in which the hook turns, this has a tendency to draw the thread 31 to 15 the closed end of the delivery opening 27, said opening being so constructed that there is no tendency or liability of the thread escaping from the delivery opening 27 after it has been brought into the same as shown in 20 Fig. 4. The thread when drawn into the delivery opening 27 also slips into the cut away portion 21 of the flange 20. The abutting end of this flange also serves to keep the thread properly located in the opening 27.

25 Referring now to my present invention it is to be noted that there are a number of important improvements in the same over the inventions shown in my said patent and said copending application. The flange on the 30 inner wall of the hook as shown in my said patent and application has been dispensed with. The ledge 11, at the top of the inner wall of the hook that extends substantially over the channel 13, and the flange 20 on the 35 periphery of the bobbin case and at the top of the same that rests on said ledge are to be noted as means by which a better bearing is secured between the hook and the bobbin case in my present invention.

40 As a feature of my present invention the fact that the bobbin thread passage 27 in the wall of the bobbin case is in a plane below the bearing between the hook and said bobbin case is to be observed. And it is to be 45 further observed that the top of the channel 13, inclines towards the periphery of the hook near the top of said channel. This channel extends upwardly to a line which is horizontally just below the extreme end 23

50 of the beak of the hook, and by inclining said channel as noted it leaves metal for the substantial ledge 11 which has been described. The said channel is also shown inclined in my said copending application, but it is not 55 claimed therein, because it is one of the elements of my present invention. The inclining of the end of the auxiliary or secondary hook 14 to correspond with the incline of the said channel is also to be observed. This 60 incline of said secondary hook will be clearly understood by referring to Fig. 2. It is to be understood that the point 23 of the beak of the hook is parallel with the periphery of the hook, and that by the construction of the 65 channel 13 and the beak of the secondary

hook 14 as explained, the point of the beak of the said secondary hook may enter the beak of the primary hook at the extreme point of the latter.

Viewing Fig. 2 now, it will be seen that the 70 bobbin case may be lowered into the hook until the flange of the case 20, rests on the ledge 11 of the hook, the said flange is of such size that its vertical face contacts with the vertical wall 12 of the hook, thereby retaining the bobbin case in a central location in the hook. The auxiliary hook 14 may now be attached to the bottom of the bobbin case by means of screws 16 (see Fig. 6) a small hub 32 being formed on the bottom of the 75 case, and fits a hole 33 through the body portion 15 of the auxiliary hook 14, thereby locating the same central with the bobbin case or the shaft 3. The diameter of the body or disk portion of the auxiliary hook is 80 the same as the diameter of the flange or wall 10 of the primary hook, so that when the said auxiliary hook is secured to the bobbin case, the case is retained on its seat in the hook by the disk portion of the auxiliary 85 hook contacting with the edge of the wall 10. The hook may now be placed on the head 5, so that the wall 7 of the hook rests on the horizontal projecting flange 6 and embraces the flange 9, thereby locating all the hook 90 parts mentioned and bobbin case central with the axis of the shaft 3, screws 8 being now inserted secure the hook to its carrier.

In the operation of the machine, the hook 95 rotates in the direction indicated by the arrow 29 in Fig. 5. The needle is thrust through the work to its full extent, and has commenced to return a sufficient extent to throw out a loop which the beak 23 of the hook enters. Immediately after the beak 100 14 of the hook enters the loop of needle thread, said loop is brought into contact with the auxiliary hook 14 which enters the beak of the hook at the point 23 of the same. This engagement between the hook 105 14 and the needle loop, and the inclined slot 25 of the hook causes the needle loop to be rapidly passed down to the end of the slot 25, which is the base or throat of the beak of the hook as before noted. The limb of said 110 needle loop that runs to the material, drops into the opening 21 between the bobbin case and inner wall of the hook, and this limb runs down to the throat 34 of the auxiliary hook 14 which retains it in this position. On 115 further movement of the primary hook, this limb of the loop swings under the bobbin case and the other limb, which runs through the needle to the supply of thread swings above the case. After the primary hook 120 has made a sufficient movement forward to bring the base of the slot 25 a little over one half around from the point of loop engagement the loop has been carried over one half 125 around the case, and the take-up now begins 130 around the case, and the take-up now begins

to draw up the loop. In Fig. 4 the position of the loop is shown after it has been drawn from around, and from under the bobbin case. It will be noted that the flange 20 still overlaps the ledge 11 of the hook, this contact continues until the loop is drawn well up or to about the position shown in Fig. 5, when the heel of the hook reaches the opening 21 in the flange of the bobbin case, thereby permitting the loop to be finally drawn from the hook. It is thus seen that the delivery of the loop is deferred until nearly all of it has been drawn up, thus preventing the same from flopping around and thereby becoming tangled or broken. A loop retainer is usually provided in this class of looper mechanisms for preventing the loop of needle thread from flopping around, but by my construction as herein disclosed the necessity for such a device is avoided.

There are many advantages in this hook mechanism over the hook mechanisms of the prior art, among which the following are mentioned. The bearing between the case and the hook being such, that the case is suspended or hangs on its bearing from the top, the liability of the case to cant or wedge is avoided, and the friction between the case and the hook is reduced to a minimum. The usual narrow flange and groove bearing between the case and the hook being avoided, the liability of the case wedging in said groove by reason of pieces of thread or other foreign matter lodging in the same is not present in this hook mechanism. In this respect it is to be noted that the end 35 of the flange 20, serves to keep the ledge 11 free from any accumulation of lint or other matter, said end being squared so that it carries along any lint or pieces of thread that may lodge on the said ledge to the heel of the looper where it is discharged.

The opening 21 between the case and the hook being at the top of the case, and above the thread delivery opening 27 in the case, and the guide 28 at, or just above said opening serves to retain the strand of bobbin thread running from the bobbin and the work, so as to guide the same in the shortest path from the bobbin to the material being stitched. The slot 27 back of the guard serves to make the bobbin case self threading or so that by one simple movement of the thread it can be threaded. The nose or point 36 in combination with the guard 28 serves to prevent the bobbin case from becoming unthreaded. In connection with this, it is noted that the bobbin is placed in the case so that it, the bobbin, in unwinding revolves in an opposite direction to that in which the hook revolves, which tends to keep the bobbin thread at the closed end of the opening 27 as shown in Figs. 4 and 5. The bearing between the case and hook being at the top of the case, the friction between the retaining

finger and the thread as the latter is drawn by the finger is reduced to a minimum.

It is obvious that when the case is provided with a bearing at or near its bottom, and is restrained from turning with the hook 70 by a finger extending from the top thereof, that the lateral strain on the case so far above its bearing causes more friction than when the bearing between the case and the hook is just below the restraining finger as in my 75 present invention. There is of course a lateral strain on the finger that restrains the bobbin case from turning with the hook, and the further this finger is above the bearing between the case and the hook the greater is 80 the tendency of this lateral strain to tip the case over, and this causes additional friction between the case and its bearing.

The auxiliary hook 14 serves to prevent side drag on the loop of needle thread as the 85 beak of the hook enters the same, and it serves to retain the limb of the loop that passes under the bobbin case in such a position that the hook may freely swing the same under the case, and it assists very much in 90 the passing of the loop around under the case with the least possible friction or strain on the thread. The body of the auxiliary hook which is in the form of a disk, serves as a means for retaining the bobbin case in its seat in the 95 hook. By reason of this auxiliary hook, and the construction of the primary hook so that the auxiliary hook can pass within the beak of the primary hook, the point of the primary hook may be at or near the top of the bobbin 100 case, and the said case is not called upon to assist in spreading of the loop, and the side drag and friction on the thread from this source is avoided. By reason of the point of the beak of the primary hook being at the top 105 of the same, the bearing between the case and the hook may be at the top of said primary hook and may extend from the said point to the heel of the hook, thereby permitting a maximum length of bearing between the 110 hook and the case. The bearing between the hook and the case being at the top of the case and hook, serves to permit the bearing between the hook and the case preceding the delivery of the loop to remain in contact until the loop of needle thread has been nearly drawn up, thus preventing the loop from 115 flopping around or from being caught by the beak of the hook as it, the hook, starts on its second rotation.

Having now described my invention what I desire to secure by Letters Patent is:

1. In a sewing machine, a looper mechanism comprising a hook having a ledge, a bobbin case having a circumferential flange that 125 is located on said ledge and means for retaining the same on the ledge, a gap in said flange for the reception of a limb of the needle thread loop, a thread passage in the wall of said bobbin case below said gap and a thread 130

guard disposed on said bobbin case above said gap by means of which the bobbin thread is retained in said gap.

2. In a sewing machine, a looper mechanism comprising a hook having a ledge and a beak, a bobbin case having a circumferential flange that is located on said ledge and means for retaining the same on the ledge, a gap in said flange for the reception of a limb of the 10 needle thread loop, a thread passage in the wall of the bobbin case below said flange for the passage of the bobbin thread into said gap and thence to the needle plate and the work, and a thread guard disposed on said 15 bobbin case above said gap by means of which the bobbin thread is guarded from being caught by the point of the beak of the hook.

3. In a sewing machine, a looper mechanism comprising a hook having a ledge, a bobbin case having a circumferential flange that is located on said ledge and means for retaining the same on the ledge, a gap in said flange for the reception of a limb of the needle 20 thread loop, a thread passage in the wall of said bobbin case below said gap, a thread guard disposed on said bobbin case above said gap, and a slot in said bobbin case by 25 means of which the bobbin thread may be

drawn into said thread passage so as to run 30 from thence upwardly back of said thread guard.

4. In a sewing machine, a stitch-forming mechanism comprising a looper having a groove formed therein and provided with a 35 ledge near its top, a bobbin case having a circumferential flange near its top that is located on said ledge, and an auxiliary hook having a beak extending into said groove.

5. In a sewing machine, a stitch-forming 40 mechanism comprising a looper having a ledge near its top, a bobbin-case having a circumferential flange located on said ledge and means for retaining the same on said ledge, a gap in said flange for the reception of 45 a limb of the needle thread loop, a thread passage in the wall of the bobbin-case below said gap, and a thread guard disposed on said bobbin case above said gap by means of which the strand of bobbin thread is retained 50 in the gap.

In testimony whereof I have hereunto signed my name in the presence of two subscribing witnesses.

WILLIAM N. PARKES.
